UNITED STATES PATENT OFFICE.

HENRY J. HEINZ, OF SHARPSBURG, PENNSYLVANIA.

DESIGN FOR A PICKLE-BOTTLE.

SPECIFICATION forming part of Design No. 14,254, dated September 4, 1883.

Application filed April 9, 1883. Term of patent 14 years.

To all whom it may concern:

Be it known that I, HENRY J. HEINZ, of Sharpsburg, in the county of Allegheny and State of Pennsylvania, have invented a new and useful Improvement in Design for Pickle-Bottles; and I do hereby declare the following to be a full, clear, and exact description thereof, reference being had to the accompanying drawings, forming a part of this specification, in which—

Figure 1 is a front view of my new pickle-bottle. Fig. 2 is a side view. Fig. 3 is a perspective view of the same bottle, Fig. 4 being a front view of a catsup and condiment bottle made of my improved design.

My improved design consists of a four-sided bottle having in some degree the form of an inverted pyramid resting on a foot or base, A, the four sides diverging from the base A to the point or shoulder B, then converging in graceful lines to C at the base of the neck D, the corners being beveled or rounded. On

two surfaces of the inverted pyramidal portion of the bottle I have delineated the design or form of a keystone in relief outlined and bounded by a raised bead, *a a a a a*. The bead, however, may be omitted, if desired. The neck D, beginning at C C, may be of any desired length or diameter, having at its junction with the body of the bottle the pear-shaped annular form, as shown in the drawings at E, and may be ornamented by rings or beads, as desired, finished at the top or mouth of the bottle so that it may be closed with a cork or with a screw-top, or with both, as shown at F.

What I claim as my invention, and desire to secure by Letters Patent, is—

The design for condiment-bottle herein described and shown.

H. J. HEINZ.
